The Vlcek Tool Company, Cleveland, Ohio, a
corporation of Ohio**

Application January 9, 1953, Serial No. 23,081

Term of patent 14 years

(Cl. D91—1)

To all whom it may concern:

Be it known that I, Lloyd F. Storie, a citizen of the United States and a resident of Shaker Heights, in the county of Cuyahoga and State of Ohio, having invented a new, original, and ornamental Design for a Hose Nozzle, of which the following is a specification, reference being had to the accompanying drawings forming a part hereof.

In said drawings, Fig. 1 is a side elevational view of a hose nozzle, showing my new design; Fig. 2 is an elevational view of the rear end of said nozzle; and Fig. 3 is an elevational view of the front end of said nozzle.

I claim:

The ornamental design for a hose nozzle, as shown.

LLOYD F. STORIE.
